WALL-MOUNTED SHELF UNIT

Robert L. Propst, Ann Arbor, Mich., assignor to Herman Miller, Inc., Zeeland, Mich., a corporation of Michigan

Filed Nov. 27, 1964, Ser. No. 82,805

Term of patent 14 years

(Cl. D33—2)

FIG. 1.

FIG. 2.

FIG. 3.

FIG. 4.

FIG. 1 is a perspective view of the front and one end of the wall-mounted shelf unit of my novel design;

FIG. 2 is an end elevational view of the storage unit;

FIG. 3 is a rear elevational view of the storage unit; and

FIG. 4 is a front elevational view of the storage unit.

The opposite end of the unit to that illustrated in FIG. 2 appears like a mirror image of that end illustrated in FIG. 2.

The dominant features of my design reside in those portions shown in full lines on the drawing.

I claim:

The ornamental design for a wall-mounted shelf unit, substantially as shown and described.
